STOKER APPARATUS

Arthur F. Schultz, Springfield, and Donald J. Mosshart, Ardmore, Pa., assignors to Westinghouse Electric Corporation, East Pittsburgh, Pa., a corporation of Pennsylvania

Application September 30, 1943, Serial No. 504,394

4 Claims. (Cl. 110—44)

This invention relates to furnace stokers, more particularly to those involving overfeed sections, and has for an object to provide improved overfeed sections for such stokers.

Another object of the invention is the provision of a stoker overfeed section involving novel grate construction.

Yet another object of the invention is the provision of an overfeed grate section whose bars may be removed and replaced entirely from above said overfeed section.

These and other objects are effected by the invention as will be apparent from the following description and claims taken in accordance with the accompanying drawings, forming a part of this application, in which:

Fig. 1 is a longitudinal sectional view through a furnace stoker installation embodying the principles of the present invention;

Fig. 2 is a side elevational view of a portion of the structure shown in Fig. 1;

Fig. 3 is an enlarged fragmentary view of a portion of the structure shown in Fig. 2 with the lower grate bars in raised position;

Fig. 4 is an end view of a portion of the structure shown in Fig. 2, with one section of the second grate bars swung to the position shown in Fig. 3;

Fig. 5 is a partially exploded view of the structure shown in Fig. 2;

Fig. 6 is a perspective view of the retaining plate;

Figs. 7 and 8 are side and top views, respectively, of one of the supporting members; and,

Fig. 9 is a plan view of a portion of the structure shown in Figs. 2 to 5, inclusive.

Referring now to the drawings more in detail, and particularly to Fig. 1 thereof, the reference character 10 indicates, in its entirety, a furnace comprising front and rear walls 11 and 12, respectively, and side walls 13. Positioned in the bottom of the furnace 10 is a stoker, indicated by the reference character 15, and comprising an underfeed section 16, followed, in the direction of fuel feed, by a first overfeed section 17 and a second overfeed section 18. Fuel is fed from the hopper 19 to the retorts 20 by conventional fuel-feeding mechanism 21, including the ram 22. Fuel fed rearwardly along the retorts 20 discharges over the dead plates 25 to the first overfeed section 17, thence to the second overfeed section 18 from which it passes to the dump plates 26, for discharge therefrom to the ash pit 27 therebelow.

Air is supplied from a suitable source (not 55

shown) to a series of first, second and third plenum chambers 28, 29 and 30, respectively. These plenum chambers are defined by the masonry wall 31, the structural members 32, 33, 35 and 36 and the bearing bracket 34. Air from the first plenum chamber 28 passes to the second chamber 29 through the opening 37 in the bearing bracket 34. Flow of air from the chamber 29 to the chamber 30 through the opening 38 is controlled by the damper 39, the amount of air supply to the last chamber 30 being dependent upon the amount of unconsumed fuel remaining in the fuel bed when it reaches the overfeed section 18. The usual siftings collecting hoppers are provided at 41 and 42 beneath the overfeed sections 17 and 18, respectively.

Referring now to the second and third sheets of the drawings, the first overfeed section 17 comprises first and second transversely extending rows of grate bars 45 and 46, respectively. These grate bars having overlapping adjacent end portions 47 and 48, pivotally connected together by pins 49 which, preferably, are of sufficient length to connect two pairs of first and second row bars 45 and 46. The second row of bars 46 are provided, adjacent their rearward ends, with transversely extending aligning pins 50 connecting a number of adjacent bars.

The first row grate bars 45 are carried by a plurality of supporting members 53, pivotally connected by pins 54 to the rearwardly-extending lugs 55 of the bearing brackets 34. Each supporting member 53 has an arm 56 extending upwardly from its forward end, the upper ends of the arms having openings 57 therethrough for passage of supporting pins or rods 58. The rearward ends of the supporting members 53 are provided with openings 59 for the reception of bearing pins 60. As best indicated in Figs. 2, 3, 40 5, 7, 8 and 9, each bearing pin 60 carries a pair of supporting members 53, the bearing pin being carried by the upper end of a link 61 whose lower end is mounted on a similar pin 62 carried by the bifurcated crank arm 63, pivotally secured to the main transversely extending shaft 64, which is oscillatable about its axis by suitable means (not shown).

It will be apparent that oscillation of the shaft 64 will operate through the crank arm 63 and link 61 to raise and lower the rear end of the supporting members 53 in pivotal movement about the pivot pins 54. As best shown in Fig. 1, the transversely extending shaft 64 is supported by the structural members 65 through bearings (not shown), the structural members being sup-

ported at their ends from the H-beams 33 and 35.

The forward ends of the first row bars 45 are provided with slots 66 providing upper bearing surfaces 67, the slots receiving the transversely extending supporting pins or rods 58, carried by the upstanding arms 56 of the supporting members 53, thereby supporting the forward ends of the first row bars 45.

As shown in Figs. 7, 8, and 9, each supporting member 53 is provided, near its rear end, with a lateral projecting lug 68, having a pair of openings 69 extending therethrough for the passage of bolts 79, these bolts serving to secure a pair of plates 71 to opposite sides of adjacent pairs of lugs 68 (Fig. 9). The plates, of the form shown in Fig. 6, are provided with pairs of openings 72 for reception of the bolts 79.

Each first row bar 45 is provided, near its rearward end, with a depending lug 73 for reception in the slot 74, provided by the spaced plates 71, the lugs 73 being provided with openings 75 adapted to be aligned with the openings 76 along the top of the plates 71, the aligned openings 75 and 76 receiving retaining pins 77, held in position by a retaining plate 78, secured by bolts 79 threaded into the openings 80 in the plate 71.

In operation, oscillation of the transversely extending shaft 64, operating through the link 61, raises and lowers the rear ends of the supporting members 53 for pivotal movement about the pivot pins 54. This movement provides for forward and backward movement of the grate bars 45 as well as vertical movement of the rear end thereof, and, due to the pivotal connection between the first row bars 45 and the second row bars 46, the forward ends of the latter are raised and lowered and the entire bars 46 reciprocated forwardly and rearwardly, with the rear ends thereof sliding upon the supporting plate structure 81 (Fig. 1).

When it is desired to remove and/or replace a bar 45, the same may be done without necessity of working from beneath the grate structure. By lifting the rear ends of a section of the second row grate bars 46, as indicated in Fig. 3, the retaining plate 78 is accessible from above the grate surface, and permits easy removal of the retaining pins 77, whereupon the depending lugs 73 at the rear ends of the first row bars 45 may be lifted vertically from the slot 74 and the connected bars 45 and 46 removed rearwardly, in the manner indicated in Fig. 5. When the rear ends of the second row bars 46 are first raised to the position indicated in Fig. 3, the aligning pin 50 may be withdrawn from the raised group, whereupon one or more pairs of bars 45 and 46 may be removed, depending upon the length of the pivot pin 49 used to connect said first and second row bars. Obviously, insertion of new bars is effected by reversal of the above described steps.

It will be apparent that the construction herein disclosed permits of ready and easy removal and assembly of grate bars by an operator working above the grate surface, thereby avoiding the prior undesirable practice involving the disconnection of securing means from beneath the stoker.

While the invention has been shown in but one form, it will be obvious to those skilled in the art that it is not so limited, but is susceptible of various changes and modifications without departing from the spirit thereof, and it is desired, therefore, that only such limitations shall be

placed thereupon as are specifically set forth in the appended claims.

What is claimed is:

1. In an overfeed section for a furnace stoker, first and second transversely-extending rows of grate bars, considered in the direction of fuel feed, each of the grate bars of said first row having a forwardly-opening slot in its forward end providing a substantially horizontal bearing surface; pivotally-mounted supporting means for the grate bars of the first row comprising a plurality of bell cranks each having an upwardly-extending arm and a rearwardly-extending arm, a horizontally-disposed rod carried by each of the upwardly-extending arms and adapted to be received in the forwardly-opening slots of a plurality of the first row grate bars with the substantially horizontal bearing surfaces of the latter resting thereon, a pair of upwardly-extending and longitudinally-spaced lugs carried by the rearwardly-extending arms of each pair of adjacent bell cranks, said pairs of lugs providing transverse slots; a depending lug at the rearward end of each of the first row bars adapted to be received in said transverse slots; means for retaining said depending lugs in said transverse slots; means pivotally connecting the forward ends of the bars of the second row to the rearward ends of the bars of the first row, whereby movement of the latter is transmitted to the former; and means for supporting the rearward ends of said second row bars.
2. In an overfeed section for a furnace stoker, first and second transversely-extending rows of grate bars, considered in the direction of fuel feed, each of the grate bars of said first row having a forwardly-opening slot in its forward end providing a substantially horizontal bearing surface; pivotally-mounted supporting means for the grate bars of the first row comprising a plurality of bell cranks each having an upwardly-extending arm and a rearwardly-extending arm, a horizontally-disposed rod carried by each of the upwardly-extending arms and adapted to be received in the forwardly-opening slots of a plurality of the first row grate bars with the substantially horizontal bearing surfaces of the latter resting thereon, a pair of upwardly-extending and longitudinally-spaced lugs carried by the rearwardly-extending arms of each pair of adjacent bell cranks, said pairs of lugs providing transverse slots; a depending lug at the rearward end of each of the first row bars adapted to be received in said transverse slots; means for retaining said depending lugs in said transverse slots; means connecting the forward ends of the second row bars to the rearward ends of the first row bars for vertical pivotal movement of the former relative to the latter, whereby the rearward ends of the second row bars may be elevated to afford access from above the stoker to the means for retaining the lugs in the transverse slots; and means for supporting the rearward ends of the second row bars.
3. In an overfeed section for a furnace stoker, first and second transversely-extending rows of grate bars, considered in the direction of fuel feed, each of the grate bars of said first row having a forwardly-opening slot in its forward end providing a substantially horizontal bearing surface; pivotally-mounted supporting means for the grate bars of the first row comprising a plurality of bell cranks each having an upwardly-extending arm and a rearwardly-extending arm, a horizontally-disposed rod carried by each of the

upwardly-extending arms and adapted to be received in the forwardly-opening slots of a plurality of the first row grate bars with the substantially horizontal bearing surfaces of the latter resting thereon, a pair of upwardly-extending and longitudinally-spaced lugs carried by the rearwardly-extending arms of each pair of adjacent bell cranks, said pairs of lugs providing transverse slots; a depending lug at the rearward end of each of the first row bars adapted to be received in said transverse slots; means connecting the forward ends of the second row bars to the rearward ends of the first row bars for relative pivotal movement; and means securing the depending lugs of the first row bars in the transverse slots, said last-mentioned means being accessible from above the stoker with the second row bars at one limit of their pivotal movement relative to the first row bars.

4. In an overfeed section for a furnace stoker, first and second transversely-extending rows of grate bars, considered in the direction of fuel feed, each of the grate bars of said first row having a forwardly-opening slot in its forward end providing a substantially horizontal bearing surface; pivotally-mounted supporting means for

5 the grate bars of the first row comprising a plurality of bell cranks each having an upwardly-extending arm and a rearwardly-extending arm, a horizontally-disposed rod carried by each of the upwardly-extending arms and adapted to be received in the forwardly-opening slots of a plurality of the first row grate bars with the substantially horizontal bearing surfaces of the latter resting thereon, a pair of upwardly-extending and longitudinally-spaced lugs carried by the rearwardly-extending arms of each pair of adjacent bell cranks, said pairs of lugs providing transverse slots; a depending lug at the rearward end of each of the first row bars adapted to be received in said transverse slots; means for retaining said depending lugs in said transverse slots; means pivotally joining the first row bars to the second row bars; means providing a support on which the rearward ends of the second row bars may slide; and means for imparting movement to the supporting means of the first row bars to move said first row bars and the second row bars.
